[57] ABSTRACT

A night sight employing a gated image intensifier is operated in conjunction with an amplitude-modulated tracking beacon on a missile and a pulsed light source for illuminating the target. The source is pulsed and the intensifier tube gated on for the target return magnet attached illumination such times that the amplitude modulated beacon intensity is at a low level for minimum viewing interference.

SHEET 2 OF 2

FIG. 3

SYNCHRONOUSLY GATED ACTIVE NIGHT SIGHT

BACKGROUND OF THE INVENTION

A class of guided missiles has been developed for tactical use which employs a command-to-line-of-sight mechanization. A sight line to a target is established with an optical sight. After launch toward the target, the missile is guided by means of an optical error sensing device which measures the error or deviation of the missile from the desired line of sight and furnishes command signals to the missile control system by means of an encoder and data link; thereby causing the missile to follow the line of sight to the target.

In order to provide a tracking source for the optical tracker, a beacon is placed on the missile. This beacon usually comprises an amplitude-modulated source of optical radiation. The modulation provides a signature which permits the tracker to discriminate against unmodulated sources such as sunlight reflections from random objects in the tracker field of view.

The optical spectrum of the beacon may be such that it can be seen by the eye. In daylight conditions the use of an optical filter would be satisfactory in reducing the beacon brightness to a tolerable level without inhibiting the ability of the gunner to maintain his line of sight on the target.

However, if a night sight is to be used with such a missile system, the degree of optical filtering necessary to reduce the beacon intensity to a tolerable level may also reduce the overall light level to a value which would seriously inhibit the tracker's ability to see the target. The instant invention solves this problem.

SUMMARY OF THE INVENTION

Since the beacon is amplitude-modulated, the radiant intensity varies with time from a very low value (essentially zero) to a peak value during each cycle.

If a night sight, which employs a gated image intensifier tube is used, the tube can be gated on for very short periods of time such that it is on at the time that the beacon radiant intensity is at its lowest value. The gating of the night sight is, therefore, so synchronized with the beacon modulation that the beacon irradiance at the night sight is kept at a tolerable value.

Since the gating of the image intensifier results in a reduction in the time during which the target is observed, the average radiant intensity from the target and scene is reduced. In order to provide the necessary target radiant intensity a pulsed illumination source is employed. The source is pulsed to illuminate the target and the image intensifier gating is timed so that the sight is gated on at the time that the radiant energy of the illuminated target returns to the night sight.

In order to provide a synchronizing signal to the illuminator and gated image intensifier tube, an optical radiant intensity sensor is employed. This sensor responds to the beacon modulation and provides means for sensing the time at which the beacon intensity is at its lowest value, thereby providing the necessary information for the synchronization of illuminator and gating.

BRIEF DESCRIPTION OF THE DRAWINGS

FIG. 1 shows the optical tracking and guidance of a missile to a target;

FIG. 2 shows the active night sight with beacon suppression;

FIG. 3 depicts the time-history relationship of the beacon modulation, illuminator pulse and the image intensifier tube gating pulse.

DESCRIPTION OF THE PREFERRED EMBODIMENT

In FIG. 1, a visual sight 10 providing a line of sight is associated with an optical tracker 11. Visually sighting to target 12 aligns the boresight axis of the optical tracker with this target. The optical tracker receives amplitude-modulated radiant pulses from a beacon 13 on missile 14. The optical tracker 11 having error sensing means therein measures the error or deviation of the missile from the desired line of sight. A command encoder 15 receives error signals from the tracker 11 and provides command signals to a command transmitter 16 which sends the corrective signals to the missile 14 thereby causing it to follow the desired line of sight to the target.

Turning to Figure 2, we see, diagrammatically, the sight 10 of the instant invention and the associated beacon suppression components. The sight 10, which is a synchronized active night sight, can be described as follows.

The beacon modulation waveform is sensed by a beacon modulation detector 20. The detected signals are sent to a crossing detector and time delay in element 21.

Electronic circuits comprising the crossing detector in element 21 detect the time at which the beacon radiant intensity has decreased to 50 percent of its peak value. A time delay of one-quarter of the modulation period is used to generate a synchronizing pulse. This synchronizing pulse triggers a pulsed illuminator 22 by way of a PRF generator 23 when the beacon radiant intensity is near its lowest level. The pulsed illuminator could, for example, comprise a narrow spectral bandwidth source such as gallium arsenide or gallium aluminum arsenide. The illuminator optical pulse is transmitted to the target 12 and reflected therefrom to the night sight 25.

A range time delay 24 operating in response to a signal from the PRF generator 23 provides a signal to the gated night sight 25 to gate the image intensifier tube on just as the optical pulse returns from the target. By these means, the target is observed when the beacon radiant intensity is at its lowest value resulting in minimum viewing interference by the beacon 13.

Additional beacon suppression is provided by a narrow optical bandpass filter 26 which passes the pulsed illuminator energy but not the radiant energy of the beacon.

The time-history of FIG. 3 shows the illuminator pulse generated after the one-quarter modulation period delay, and the image tube gate pulse being generated at the time of the returning reflected target pulse.

The device of the instant invention could, for example, incorporate a second generation image intensifier tube employing a single photoemissive photocathode, a microchannel plate amplifier and a single phosphor screen; such tube providing speed of response and peak pulse capabilities compatible with the overall system requirements of this device.

While a preferred embodiment of the invention has been disclosed, it should be clear that variations and alterations thereof can be made while remaining within the scope of the invention which is only limited by the following claims.

We claim:

1. An optical command-to-line-of-sight guidance system having an active night sight for use with a missile having an amplitude-modulated beacon of optical radiation thereon, said system comprising:

photoresponsive means for detecting the radiant energy amplitude of the missile beacon;

electronic circuit means including means for determining the time at which the beacon amplitude has decreased to a pre-determined level from its peak amplitude and for generating a synchronizing signal thereat;

means for generating an illumination pulse along the line of sight toward a missile target in response to said synchronizing signal;

a gated night sight capable of being gated on in response to an applied signal;

range time delay means responsive to a signal derived from said synchronizing signal to gate on the gated night sight; whereby the night sight is gated on

when the beacon amplitude is at a low level and the pulsed illumination reflected from said target has returned to said night sight.

2. The system of claim 1 wherein said electronic circuit means includes further means for establishing a time delay in said synchronizing signal; said time delay being on the order of one-quarter of the beacon modulation period.

3. The system of claim 2, further including a pulse repetition frequency generator for receiving said synchronizing signal and utilizing said synchronizing signal for triggering the illumination pulse, said generator further activating said range time delay for gating on said night sight;

said generator further activating said range time delay for gating on said night sight.

4. The system of claim 3 including a narrow bandpass filter associated with said gated night sight.
